CLAIM

The ornamental design for an air curtain diffuser as shown and described.

DESCRIPTION

1. Air curtain diffuser

1.1 :Front side perspective view

1.2 :Top plan view

1.3 :Front side elevation view

1.4 :Rear side elevation view

1.5 :Bottom plan view

1.6 :Right side elevation view

1.7 :Left side elevation view

(Continued)

The broken lines shown in the figures are for the purpose of illustrating portions of the air curtain diffuser that form no part of the claimed design.
